ATTORNEY

UNITED STATES PATENT OFFICE.

CHARLES EDWARD ARCHER, OF SUMTER, SOUTH CAROLINA.

BRAKE.

Application filed August 27, 1923. Serial No. 659,661.

To all whom it may concern:

Be it known that I, CHARLES E. ARCHER, a citizen of the United States, residing at Sumter, in the county of Sumter and State 5 of South Carolina, have invented new and useful Improvements in Brakes, of which the following is a specification.

This invention relates to brakes for railway cars, the general object of the invention 10 being to provide means for supporting the brake beams so as to eliminate the use of bolts, pins and brake chains.

Another object of the invention is to so 15 form the parts that the beams can be easily and quickly placed in position or taken down.

This invention also consists in certain other features of construction and in the combination and arrangement of the several parts, to be hereinafter fully described, 20 illustrated in the accompanying drawings and specifically pointed out in the appended claims.

In describing my invention in detail, reference will be had to the accompanying 25 drawings wherein like characters denote like or corresponding parts throughout the several views, and in which:—

Figure 1 is a plan view of a portion of a 30 railway car truck showing the invention in use.

Figure 2 is a side view.

Figure 3 is an end view.

Figure 4 is a section on line 4—4 of Figure 35 1.

Figure 5 is a section on line 5—5 of Figure 1.

Figures 6, 7 and 8 are detail views.

In these views 1 indicates the brake beam 40 and 2 indicates the bolster. My invention comprises U-shaped members 3 for holding the brake beam, one limb of each member being shorter than the other and a spring latch 4 being connected with the long limb 45 adjacent the end thereof. The member is of T-shape in cross section and its ends are held in the boxes 5 and 6 which are formed with openings 7 and 8 of T-shape to receive the limbs of the member. These boxes are

connected with the bolster and the opening 50 7 of the box 5 has its end closed so that this opening acts as a keeper for the short limb of the member. The long limb will pass entirely through the opening 8 of the box 6 with the spring latch 4 engaging the rear 55 end of the box and thus acting to hold the member in position. When the member is to be removed to free the beam it is necessary to push in this spring latch before the member can be drawn from the boxes. 60

From the foregoing it will be seen that no 65 bolts or pins are used which are liable to be lost or left out and the brake chains are also eliminated. The members are simply shoved into the boxes, to hold the beam in place, the spring latches automatically locking the members in position. When the beam is to be removed the latches are pressed inwardly so that the members can be withdrawn from the boxes. 70

Lugs 9 are connected with the brake beams to prevent lateral movement of the parts.

It is thought from the foregoing description 75 that the advantages and novel features of my invention will be readily apparent.

I desire it to be understood that I may make changes in the construction and in the combination and arrangement of the several parts, provided that such changes fall within the scope of the appended claims. 80

What I claim is:—

1. A support for a brake beam comprising a U-shaped member, boxes for receiving the ends of the member and a spring latch on 85 one end of the member for engaging a part of one box to hold the member in position.

2. A support for a brake beam comprising a U-shaped member having one limb longer than the other, a pair of boxes for receiving the ends of the limbs, one box having its rear closed and engaging the end of the short limb and a spring latch on the long limb for engaging a part of the box to hold the member in position. 95

In testimony whereof I affix my signature.

CHARLES EDWARD ARCHER.
